UNITED STATES PATENT OFFICE.

ADDISON NORMAN, OF DAVISVILLE, CANADA.

DESIGN FOR A PLATE OR SIMILAR ARTICLE.

SPECIFICATION forming part of Design No. 33,416, dated October 23, 1900:

Application filed July 7, 1900. Serial No. 22,885. Term of patent 7 years.

To all whom it may concern:

Be it known that I, ADDISON NORMAN, residing in Davisville, in the county of York and Province of Ontario, Canada, have invented and produced a new and original Design for Plates or Similar Articles of Manufacture, of which the following is a specification.

My design has for its object the ornamentation of plates and similar articles of manufacture.

In the accompanying drawings, Figure 1 is a top plan view of a plate ornamented with my design, and Fig. 2 is an elevation of the same.

The characteristic feature of my design is an ornamental border arranged near the edge of the plate and made up of a series of the conventional figure known as the "fylfot" or "swastika." These figures are arranged be-

tween parallel lines or bands which constitute part of the ornamental border.

In the center of the plate is a fylfot figure surrounded by a line or narrow band. This central figure is larger than the individual 25 fylfot figures in the border.

By the term "similar articles of manufacture" as used in this case I mean dishes to which the design may be applied, such as the dishes of a dinner set, of which the plate represented in the drawings is a single member.

Having described my invention, what I claim, and desire to secure by Letters Patent, is—

The design for a plate or similar article, 35 substantially as shown and described.

ADDISON NORMAN.
